AARON J. TYLER, OF ROCHESTER, NEW YORK, ASSIGNOR TO FRANK S. BIDWELL, OF SHORTSVILLE, NEW YORK.

FORCE-PUMP.

1,039,336.

Specification of Letters Patent. Patented Sept. 24, 1912.

Application filed May 17, 1911. Serial No. 627,697.

To all whom it may concern:

Be it known that I, AARON J. TYLER, a citizen of the United States, residing at Rochester, in the county of Monroe and 5 State of New York, have invented certain new and useful Improvements in Force-Pumps, of which the following is a specification.

This invention relates to pumps and more 10 particularly to that general class known as force pumps.

The object of the invention is to provide a force pump of simple and durable construction, capable of being used for pumping 15 either water or air without the necessity of disturbing the valvular arrangement of the pump or in any manner altering or changing the construction thereof.

A further object of the invention is to 20 provide a pump, the valve and piston of which are so constructed as to occupy the least possible amount of space within the pump cylinder and to give thoroughly reliable service under all conditions.

25 A further object is to provide means whereby the lower valve and seat, as well as the piston, may be quickly reversed so as to reverse the action of the pump, when desired.

30 A further object is to provide novel means for clamping the cup-shaped leather washer or piston in engagement with the piston head, and means for forcing the washer or piston in contact with the interior wall of 35 the cylinder so as to prevent leakage between the parts and at the same time insure uniform wear on said piston.

A still further object of the invention is 40 generally to improve this class of devices so as to increase their utility, durability and efficiency.

45 Further objects and advantages will appear in the following description, it being understood that various changes in form, proportions and minor details of construction may be resorted to within the scope of the appended claims.

50 For a full understanding of the invention and the merits thereof, reference is to be had to the following description and accompanying drawings, in which:

55 Figure 1 is a vertical sectional view of a force pump constructed in accordance with my invention; Fig. 2 is a side elevation; Fig. 3 shows a bottom plan view, transverse

sectional view, top plan view and side elevation of one of the disks constituting the piston head; Fig. 4 shows a bottom plan view, transverse sectional view, top plan view and side elevation of the other disk of 60 the piston head, the cup-shaped leather washer or piston being shown in position on said disk in the side view thereof; Fig. 5 shows a bottom plan view, transverse sectional view, top plan view and side elevation 65 of the lower valve; Fig. 6 shows a top plan view and an edge view of the piston valve; Fig. 7 shows a top plan view and side elevation of the cup-shaped leather washer for the piston, the washer being also shown 70 in section, after being forced into proper shape; Fig. 8 is a top plan view and an edge view of the valve for the lower valve seat.

Corresponding and like parts are referred 75 to in the following description and indicated in all the views of the drawings by the same reference characters.

The improved force pump forming the subject matter of the present invention comprises a cylinder 5 having sleeves 6 rigidly secured to the opposite ends thereof and provided with exterior threads 7 for engagement with the adjacent cylinder heads, indicated at 8 and 9. The interior walls of 80 the sleeves 6 are preferably provided with circumferential shoulders 10 for contact with the adjacent ends of the cylinder 5 so as not to offer any surface obstruction within the cylinder which would tend to impede 85 the flow of liquid when the pump is in operation.

The cylinder heads 8 and 9 are provided with laterally extending nipples 11 and 12 having exterior threads 13 for engagement 95 with correspondingly threaded pipe sections, the nipple 11 constituting an inlet port and the nipple 12 an outlet port. The cylinder head 8 is provided with a gland 14 and an inwardly extending flange 15, there 100 being a gasket 16 interposed between the flange 15 and the end of the adjacent sleeve 6 in order to prevent leakage between the parts.

Slidably mounted in the cylinder 5, is a 105 piston rod 17, one end of which projects through the gland 14, while the other end thereof is provided with a circumferential stop shoulder 18 defining a reduced cylindrical extension 19, the free end of which is 110

exteriorly threaded, as indicated at 20. Mounted on the inner end of the rod 17, is a piston head, preferably formed of co-acting disks 21 and 22, each disk in turn being formed of inner and outer concentric rings connected by radiating ribs 23 defining intermediate ports 24 to permit the passage of air or liquid through the valve, as the case may be. One side of the disk 21 is provided with a curved wall 25 which forms a seat for a cup-shaped leather washer or packing 26, said disk being also provided with an annular shoulder 27 arranged at an angle to the radius of the disk and at a right angle to the curved wall 25 of the disk and forming an abutment for the adjacent end or edge of the cup-shaped washer or packing 26, the latter being preferably placed on the disk with the hair side of the leather next to the interior wall of the cylinder. The edge of the inner disk 22 is curved at 28 to conform to the curvature of the wall 25 and is adapted to bear against the inner face of the cup-shaped leather washer or packing adjacent the shoulder 27 of the disk 21 for the purpose of clamping the same on the piston head. It will be observed that the inner ring and the radial arms of each disk occupy substantially the same diametrical plane so that the two disks may fit close together thereby reducing the space taken up in the cylinder by them and effectually securing the packing. The wall of the opening in the inner ring of the disk 21 is smooth and unobstructed and fits over the cylindrical extension 19 of the piston rod for contact with the shoulder 18 thereof, while the wall of the opening in the inner ring of the disk 22 is threaded for engagement with the threads 20 on said piston rod so that by rotating the disk 22 on the threaded end of the rod, not only will the leather washer or piston 26 be firmly clamped in engagement with the disk 21, but both disks will be securely held against accidental displacement on the rod 17.

One side of the disk 22 is concaved at 29 to form a seat for a valve 30, the latter being preferably made of fabric packing, such as 50 cloth or wire, and adapted to normally close the ports 24 in the co-acting disks constituting the piston head. The valve 30 is normally flat, and is retained in position on its concaved seat 29 by means of a nut 31 55 engaging the threaded end of the rod 17 and bearing against a metallic or other washer 32. It will here be noted that as the valve 30 is normally flat, when the nut 31 is adjusted on the threaded end of the rod, 60 the central portion of the valve will be forced inwardly in contact with the concaved seat 29 so as to frictionally hold the outer edge of the valve in contact with the outer ring of the disk 22. It will also be noted 65 that the nut 31, in addition to retaining the

valve 30 in position on the disk 22, also assists in preventing accidental displacement of the piston head.

One side of the disk 22, at the curved portion 70 28 thereof, is preferably cut-away to form an annular groove 33, so as to permit a portion of the air or water passing through the ports 24 of the piston head to come in contact with the inner face of the leather washer 26 and force the hair side of 75 the leather in contact with the interior wall of the cylinder 5, thus not only to prevent leakage between the parts, but also to insure a uniform wear on the washer. That portion of the disk 21, opposite the curved 80 wall 25 thereof, is preferably dished, as indicated at 34, while that portion of the mating disk 22, opposite the concaved face 29, is also preferably dished, as indicated at 35.

Disposed at the lower end of the cylinder 85 5 and preferably arranged at substantially right angles to the outlet port 12, is an auxiliary disk 36 having a laterally extending anchoring flange 37 which is supported on a flange 38 extending inwardly from the 90 lower head 9 of the cylinder and similar in construction to the flange 15. A gasket 39 is preferably interposed between the flanges 37 and 38 and a similar gasket 40 between the flange 37 and end of the adjacent sleeve 95 6 in order to prevent leakage of air or water when the pump is in operation. One side of the disk 36 is provided with a concaved face 41 constituting a seat for a valve 42, the latter being similar in construction to the valve 30 and retained in position on its seat by a screw 43, the threaded shank of 100 which engages a correspondingly threaded opening 44 formed in said auxiliary disk. The inner and outer rings comprising the 105 auxiliary disk 36 are connected by radiating ribs 45 to form intermediate ports 46, through which the air or water is discharged on the downward stroke of the piston, the outer ring of the auxiliary disk, at 110 the concaved face thereof, being preferably formed with a relatively short inwardly extending flange 47 against which the outer edge of the valve 42 rests when the latter is in closed position.

When the device is used for pumping water, the operation thereof is as follows: On the upward stroke of the piston, the valve 42 will be moved to closed position and a partial vacuum formed between said valve and the piston, with the result that as the piston continues to travel in an upward direction, the water above said piston will open the valve 30 and pass to the front thereof. On the downward stroke of the 125 piston, the valve 42 will be moved to open position so that the water in the cylinder 5 will be forced through the ports in the valve seat 41 and out through the discharge port at the nipple 12. It is obvious that the 130

pump will operate in exactly the same manner when pumping air.

Attention is here called to the fact that the parts comprising the piston head, as well as the parts comprising the lower valve, may be reversed so as to reverse the action of the pump when desired, in which event, the member 9 will constitute the suction head and the member 8 the force head of the pump, as will be readily understood.

It will also be noted that the leather washer 26 is normally flat and will be forced into substantially cup-shape by engagement with the co-acting disks comprising the piston head without the formation of any wrinkles or creases whatever, thus permitting a nice fit between the leather washer and cylinder and insuring the proper operation of the pump at all times.

20 It will of course be understood that the disks may be formed with any desired number of radiating ribs and ports, and that the piston rod may be provided with any suitable operating handle or said pump operated from some extraneous source of power without departing from the spirit of the invention.

Having thus described the invention, what is claimed as new is:

30 1. A pump including a cylinder having inlet and outlet ports, a valve arranged near one of the ports, a piston rod operating within the cylinder, a piston head mounted on the rod and including co-acting disks having 35 ports formed therein, one of said disks being provided with a concaved outer face constituting a valve seat, a flexible valve secured on the piston rod and normally engaging said seat, and a flexible packing interposed 40 between and held by the disks.

2. A pump including a cylinder having inlet and outlet ports, a piston rod operating within the cylinder, a piston head carried by the rod and including co-acting 45 disks having radiating ribs defining intermediate ports, one of said disks being provided with a concaved outer face constituting a valve seat and the other with a curved wall, a flexible packing interposed between 50 and held by the disks and bearing against said curved wall, a valve engaging the concaved valve seat, and an auxiliary valve arranged at one end of the cylinder.

3. A pump including a cylinder having 55 inlet and outlet ports, a valve arranged near one of the ports, a piston rod operating within the cylinder and provided with a reduced extension defining an annular stop shoulder, said extension having a threaded 60 extremity, a piston head including co-acting disks, one of which is smooth-bored and bears against the stop shoulder, the other disk being threaded to fit on the extremity of the piston rod and provided with a concaved outer face constituting a valve seat, a

valve engaging said seat, and a cup-shaped flexible packing interposed between the disks, the threaded disk clamping the packing against the first-mentioned disk and said disk against the stop shoulder.

4. A pump including a cylinder having inlet and outlet ports, a valve arranged near one of the ports, a piston rod operating within the cylinder and having one end thereof provided with an annular stop shoulder defining a reduced cylindrical extension, the free end of which is threaded, a piston head mounted on the rod and including co-acting disks, one of which bears against the stop shoulder, one disk being smooth-bored and the other disk being threaded to engage the threaded portion of the rod and provided with a concaved outer face constituting a valve seat, both of said disks being provided with ports, a valve engaging the concaved face of the adjacent disk, a flexible packing interposed between and held by said disks, and a nut engaging the threads on the rod and retaining both disks and the valve thereon.

5. A pump including a cylinder having inlet and outlet ports, a valve arranged near one of the ports, a piston rod operating within the cylinder, a piston head carried by the rod and including co-acting disks one of which is provided with an internal longitudinally curved wall and the other with a concaved outer face constituting a valve seat and having its outer edge opposing the outer wall of the first-mentioned disk, both of said disks being provided with ports, a valve bearing against the valve seat, and a flexible packing interposed between and held by the said curved wall and the edge opposing the same, the outer edge of one of the disks being cut away adjacent the inner face of the packing to form an annular groove.

6. A pump including a cylinder having inlet and outlet ports, a valve disposed near one of the ports, a piston rod working within the cylinder, a smooth-bored disk fitted on the end of said rod and provided at its outer edge with an extended flared inner surface and an annular shoulder at the inner edge of said surface, said shoulder being disposed obliquely to the radius of said disk and at a right angle to the said flared surface, a packing fitted against said surface with its edge bearing squarely against said shoulder, a second disk fitted on the piston rod and having its outer edge flared to conform to the outer edge of the first-mentioned disk and bearing on the packing and clamping the same against said surface and the said shoulder, a valve fitting against said second disk, and a securing nut mounted on the piston rod and bearing against said valve.

7. A pump including a cylinder having oppositely disposed exteriorly threaded sleeves, correspondingly threaded heads engaging the threads on said sleeves and pro-

vided with inlet and outlet ports, said heads being provided with inwardly extending flanges, a washer interposed between the flange of one of the heads and the adjacent sleeve, a disk disposed at the outlet port and having a laterally extending flange supported on the flange of the other head, said disk being provided with ports and having a concaved face constituting a valve seat, a valve engaging said seat, a washer interposed between the flange on the disk and the flange on the adjacent head, a second washer interposed between the flange on the disk and the adjacent sleeve of the cylinder, a piston rod op-

erating within the cylinder, a piston head 15 carried by the rod and including co-acting ported disks, a valve carried by one of the disks, and a flexible packing interposed between both disks, said valves opening in the same direction and arranged to operate alternately.

In testimony whereof, I affix my signature in presence of two witnesses.
